BILLFOLD

Ignatz Sahula, Dallas, Tex.

Application May 21, 1945, Serial No. 594,947

4 Claims. (Cl. 150—38)

1

This invention relates to pocket billfolds and other receptacles of a similar nature and it has particular reference to a billfold made of a single piece of material.

The principal object of the invention is to provide a receptacle in the nature of a pocket billfold of a single piece of material such as leather, pliable plastic, fabric or the like, folded from a pre-cut blank in such manner that only one side of the material will be revealed over the entire finished fold. The receptacle thus produced presents a neat appearance, with no tabs, catches, straps or loops revealed and provision is made for a certain degree of expansion of various pockets to accommodate an average bulk of articles usually carried in a receptacle of this character.

Another object of the invention is to provide a pocket receptacle whose peculiar construction, when folded, presents various compartments and pockets in a most accessible manner, certain of which provide concealed or secret compartments and all of them are free of unfinished edges and are provided with closures against entry of foreign matter.

With the foregoing objects as paramount, the invention has further reference to certain features of accomplishment which will become apparent as the description proceeds, taken in connection with the accompanying drawings wherein:

Figure 1 is a plan view of the blank of one form of receptacle.

Figure 2 is a perspective view of a billfold formed from the blank shown in Figure 1, in opened position with one pocket partially completed.

Figure 3 is a similar view, showing the billfold in partially opened position.

Figure 4 is a plan view of the blank of a slightly modified form of the invention, and

Figure 5 is a perspective view of a billfold formed from the blank in Figure 4, in opened position, revealing the covering flap of one of the auxiliary pockets or compartments.

Continuing with a more detailed description of the drawing, reference is primarily made to Figure 1, showing the blank form from which the billfold shown in Figures 2 and 3 is made and which blank is generally designated by reference numeral 10. This blank, which is of a single piece of leather, fabric or pliable plastic, is made up of parallel, intermediate sections A, B, C and D, which, when folded in the manner to be presently explained, form the body of the purse or

2

billfold. The section C is of greater length than the companion sections A, B and D to define end sections E.

The end sections E are identical in shape and each has extensions 11 on each side thereof defining tabs 12. The circular design of the edges 13 of the end sections E has little significance in the present design of the billfold, except to present a more aesthetic appearance than if these edges were cut on a straight line. Any design may be carried out to ornament these edges, which become the tops of auxiliary pockets or compartments to be later identified and described, when the blank is folded along predetermined lines:

To produce the billfold shown in Figures 2 and 3, the sections A and B are folded onto section C along line c', which fold includes the folding of extensions 11 of one side of end sections E, since lines c, separating these extensions are continuations of the fold c'. The extensions 11 at the opposite end of end sections E are then folded onto the latter along lines c, parallel with the lines first mentioned, identified by the same reference character c. The section D is then folded inwardly along line b, to produce a facing tab or separator.

One of the end sections E is folded along line d to overlie section B, containing slits 14 and it is apparent that the exposed side of section B is the finished side of the material. The tabs 12 are then inserted through their opposing slits to form one of the auxiliary end pockets. Following this latter operation, the opposite end section E is folded along line d to overlie the opposite end of section B and the tabs 12 are manipulated into the slits 14 corresponding to the latter tabs. This will form the companion end pocket.

The inside of the elongated pocket, formed by the folds already made is inspected to determine if the tabs 12 of the extensions 11 of each end section E are lying flat against the inner surface of section B, after which the section A is folded along line a and tucked into the space between sections B and C. These operations complete the billfold shown in Figures 2 and 3.

It will be observed that a circular offset 15 is cut at each end at the juncture between the tab ends 11 and the end sections E next adjacent the fold line b of the section C. The offsets have the effect of reducing the width of the auxiliary receptacles produced by the end sections E, so that the outer lip of the elongated receptacle defined by the major sections A, B, C and D will extend above the common plane of the said auxil-

iary receptacles and the inner lip of the elongated receptacle or pocket.

The neck 12^a forming the connection between the end sections E and their extensions 11 is slightly less in width than the length of the slit 14 in which it is adapted to lie. This fact, combined with the inclined positions of the receiving slits 14, permits the auxiliary pockets or receptacles to be expanded individually as to width without undue strain on the retaining tabs 12, to increase the capacity thereof. It is to be particularly noted that there are no transverse edges within the pockets, as may be presented by folds or tab retaining slots, to interfere with the insertion of articles into these pockets. Moreover, by virtue of the particular manner of fastening the extensions to form the auxiliary pockets, the latter are capable of individual expansion and such material as may be stored in these pockets, however bulky, will have no tendency to distort the elongated pocket or receptacle and vice versa.

Among the advantages of the single piece billfold described is the feature of interlocking the various parts of the blank in folded position on one side, which obviates the necessity of turning the billfold from side to side to gain access to the interlocking elements.

An examination of Figure 1 will disclose that by making section A nearly as wide as sections B and C so that it will extend, in folded position, almost to the bottom of the elongated receptacle, a concealed compartment will be formed thereunder in which to place seldom used papers or surplus currency. However, with the comparatively narrow section D, as shown, it may either be disposed between the sections A and C in the manner shown in Figures 2 and 3, or it may serve as a flap to overlie the space between these sections and lie between the end pockets or receptacles and the section B, to close the elongated pocket.

In Figures 4 and 5 a slight modification in the marginal design of the blank is shown, resulting in a slight difference in the appearance of the billfold formed thereby, although the same general results are attained. The blank 16, as in the preceding case, is composed of the principle sections F, G, H and I, constituting the body of the billfold. The section H is elongated to define end sections J, each of which has an extension 17 on each side thereof defining tabs 18, receivable in slits 19 in the section G, in the manner to be described presently.

The differentiating characteristic of the present form of billfold over that earlier described lies in the provision of flaps 20 on the ends of the end sections J, serving to close auxiliary compartments formed by the end sections, and the comparatively wide section I, which provides a concealed compartment in the billfold proper.

To form the billfold shown in Figure 5, sections F and G are folded onto section H along line c'', of which, as apparent in Figure 4, lines d' at each end are continuations, hence the upper extensions 17 of the end sections J are folded simultaneously. Next, the opposing or lower extensions 17 are each folded onto their respective end sections J along lines d' in offset relation to folding line b'. Following this operation, section I is folded inwardly along line b'. It is now apparent that all longitudinal folds have been completed and to form the end pockets, each end section J is folded along its respective folding line e and the tabs 18 of extensions 17 are manipulated into the slits 19 of section G, which they now overlie. The final 75

folding operation is to turn section F inwardly along line a' and tuck the same between sections I and G, in which position it will lie flush against the tabs 18 inside of the latter section, to conceal the same and to provide a smooth inner lining for the elongated receptacle. Also, this manner of folding section F provides an inner wall behind which papers or currency may be kept.

After the folding and locking operations described, the flaps 20 are folded inwardly along lines f, to lie between the body proper and the said auxiliary pockets, in the manner shown in Figure 5.

It will be observed that by virtue of the offset 15 produced by the curve g at the juncture between the end sections J and body section H at the lower corners, and by making the sections F, G and I narrower than section H, the inner lip of the main receptacle of the billfold at a' will be below the 20 outer lip thereof at b' for convenient access to the receptacle.

It is further apparent that by virtue of the particular design of the blank and the manner of folding to produce the billfold, the end receptacles 25 are easy of access and various articles such as cards, small papers and the like may be quickly selected and removed from the pockets by bending the body in the manner shown in Figure 5.

Manifestly, the construction as shown and described is capable of some modification and such modification as may be construed to fall within the scope and meaning of the appended claims is also considered to be within the spirit and intent of the invention.

35 What is claimed is:

1. A billfold, comprising a single piece of stock material formed as a blank having four body sections defined by parallel folds, the outer sections being superimposed upon the juxtapositioned 40 inner sections to form the side walls of an elongated pocket, one of said inner sections being provided with pairs of slits adjacent both ends respectively, the other of said inner sections being elongated to define end sections having oppositely directed tabs on each side thereof, the sides of the end sections carrying the tabs being folded under their related end sections, and the end sections being folded upon the slotted body section with the tabs interlockingly engaging their related 45 slits to form auxiliary pockets and to hold all of 50 said sections in folded relationship; the slits of each pair being oppositely inclined and slanting inwardly towards the center of the slotted body section; and the necks between the tabs of the 55 end sections being correspondingly inclined and of less width than the length of the said slits, whereby the auxiliary pockets may be expanded as to width to increase the capacities thereof without straining the said tabs and without distorting the elongated pocket.

60 2. In a billfold as set forth in claim 1, said end sections each having a tab at its outer end which when folded under the open ends thereof form a closure for the related auxiliary pocket.

65 3. In a billfold as set forth in claim 1, the elongated body section being wider than the other body sections, whereby the two outer body sections will form with their adjacent body sections, when they are tucked into the elongated pocket 70 between the inner body sections, concealed elongated pockets each opening at the bottom of said first mentioned elongated pocket.

75 4. In a billfold as set forth in claim 1, one of the outer body sections being relatively narrow and serving as a closure flap for the elongated

socket, and the other outer body section being tucked into the elongated pocket to provide a concealed elongated pocket opening at the bottom of said first mentioned elongated pocket.
